(No Model.)

A. E. JERNANDER.

MACHINE FOR CLEANING OR SCOURING WHEAT.

No. 359,867.

Patented Mar. 22, 1887.

UNITED STATES PATENT OFFICE.

ANDERS EMIL JERNANDER, OF ROCHESTER, MINNESOTA.

MACHINE FOR CLEANING OR SCOURING WHEAT.

SPECIFICATION forming part of Letters Patent No. 359,867, dated March 22, 1887.

Application filed August 17, 1886. Serial No. 211,137. (No model.)

To all whom it may concern:

Be it known that I, ANDERS EMIL JERNANDER, a resident of Rochester, in the county of Olmsted and State of Minnesota, have invented 5 certain new and useful Improvements in Machines for Cleaning or Scouring Wheat; and I do hereby declare that the following is a full, clear, and exact description of the invention, which will enable others skilled in the art to 10 to which it appertains to make and use the same, reference being had to the accompanying drawings, which form a part of this specification, and in which—

Figure 1 is a side view of my improved 15 wheat cleaning or scouring machine. Fig. 2 is an end view of the same. Fig. 3 is a longitudinal vertical sectional view of the machine, and Fig. 4 is a vertical cross-section.

Similar letters of reference indicate corresponding parts in all the figures.

My invention has relation to the class of 25 machines for cleaning or scouring wheat, and which are also adapted for hulling or scouring other grain, in which beaters having radiating arms revolve within perforated cylinders 30 revolving in the opposite directions to said beaters; and it consists in the improved construction and combination of parts, as will be hereinafter more fully set forth and claimed.

In the accompanying drawings, the letter A 35 indicates a rectangular frame, having bearings B in its end pieces, in which bearings a horizontal square beater-shaft provided with journals C revolves, said shaft having a band-pulley, D, or similar gear at one end and a pinion, E, secured upon its other end. The square beater-shaft has a number of beater-arms, F, secured upon it, the said beater-arms having square perforations at their middles, 40 by which they are secured upon the shaft, being alternately secured at right angles to each other.

The cylinder G has sleeves H H at the centers of its heads. Said sleeves project outward and are journaled in bearings upon the cross-pieces I inside of the bearings for the beater-shaft. The entire surface of the cylinder is formed with long perforations J, the edges of which project inwardly and assist in 45 abrading the hulls of the grain, while the

broken hulls, dust, and other impurities will pass out through the perforations.

The head of the cylinder is provided at the feed end with an internally-cogged flange or rim, L, which is engaged by a pinion, M, upon 55 the inner end of a counter-shaft, N, having a cog-wheel, O, meshing with the pinion upon the beater-shaft, so that the cylinder may be revolved slowly in a direction opposite to the direction in which the beater-shaft revolves. 60

The cylinder is surrounded by a casing, P, one end of which is provided with a feed-chute, Q, the lower end of which passes into the cylinder through the sleeve at its end, admitting of grain being fed into the cylinder. A blast-fan, R, is attached to the casing for forcing a 65 current of air into the cylinder and driving out through its sides the hulls, dust, and other impurities, which will fall into a hopper, S, forming a part of the casing surrounding the 70 cylinder and extending nearly its entire length; or they may be drawn out by an exhaust-fan.

The discharge end or head of the cylinder is provided with a number of apertures, T, formed with sliding doors U, and the cleaned 75 and scoured wheat or hulled grain is discharged through these apertures, the doors being withdrawn until all the wheat or grain has passed out, whereupon they are again closed, and the discharged wheat or grain falls into a 80 spout, V, secured under the discharge end of the cylinder.

It will be seen that when wheat or grain is fed into the cylinder and it is revolved, the beater-shaft revolving with a considerably 85 greater speed and in an opposite direction within it, the wheat or grain will be beaten and scoured by the beater-arms and forced violently against the perforated sides of the cylinder, and that the hulls and other impurities 90 will be rubbed off the grain, and that the current of air which passes through the cylinder will force the hulls and impurities out through the perforations, while the whole grain will pass out by the discharge-apertures when the 95 latter are opened.

The beater-arms are removable from the shaft, so that if they should become either worn out or otherwise damaged they may be removed and new ones put in their places, the 100

arms fitting freely upon the shaft by means of their central perforations.

If the edges at one side of the arms become worn out, the arms may be reversed upon the shaft, bringing the other sides of the arms to face in the direction of the revolution of the shaft, so that the arms will present flat faces with sharp edges, instead of rounded sides, which would be apt to pass too easily through the grain without scouring or hulling it.

Having thus described my invention, I claim and desire to secure by Letters Patent of the United States—

In a machine for cleaning or scouring wheat, 15 the combination of a frame having a cross-piece at each end within the ends of the frame, a perforated cylinder journaled in bearings upon said cross-pieces and having its heads provided with sleeves, the discharge-head be-

ing also provided with apertures, and doors 20 adapted to slide over said apertures, a shaft journaled at its ends upon the ends of the frame and extending through said cylinder and having beater-arms upon its intermediate portion, a casing the lower portion of which is provided 25 with a hopper and a spout, a feed-chute upon one end of said casing, the lower end of which projects through the sleeve at the feed end of said cylinder, and means, substantially as described, for rotating said shaft and cylinder in opposite directions.

In testimony that I claim the foregoing as my own I have hereunto affixed my signature in presence of two witnesses.

ANDERS EMIL JERNANDER.

Witnesses:

M. J. DANIELS,
G. D. PARMELE.
